J. YOUNGBERG

SUPPORT FOR TAILORS' IRONS

Filed Dec. 29, 1922

UNITED STATES PATENT OFFICE.

JOHN YOUNGBERG, OF LOS ANGELES, CALIFORNIA.

SUPPORT FOR TAILORS' IRONS.

Application filed December 29, 1922. Serial No. 609,629.

To all whom it may concern:

Be it known that I, JOHN YOUNGBERG, a citizen of the United States, residing at Los Angeles, in the county of Los Angeles, State of California, have invented a new and useful Support for Tailors' Irons, of which the following is a specification.

An object of this invention is to provide simple and convenient means to lessen the labor of tailor's work in pressing seams, with the tailor's goose or pressing iron.

In tailor shops the pressing of garments is done upon tables that support the garment the seams of which are to be pressed, and in pressing the coat sleeves it is customary to slip the sleeves on to a sleeve board which supports the same a considerable distance above the table; but in pressing other seams the garment is laid directly on the table and therefore the pressing iron has to be lifted from, and returned to the level of the table, and as the pressing iron is naturally quite heavy the work is quite laborious. An object of this invention is to provide means for supporting the iron at different heights in such a manner that the tailor can perform the work of pressing the seams with a minimum amount of effort.

An object of the invention is to provide a support of the character set forth so constructed that it can be instantly moved from one fixed adjustment to another so that the tailor may quickly change the bracket from one position to another without inconvenience.

An advantage of this invention is that the tailor is relieved from having to lift the full weight of the pressing iron and is enabled to operate the same by a downward pressure and slight release from such pressure as occasion may require.

An object is to provide a support for tailor's use a pressing iron support that will normally sustain the iron as stated and will allow great freedom of movement within a large area.

Other objects, advantages and features of invention may appear from the accompanying drawing, the subjoined detail description and the appended claims.

The accompanying drawing illustrates the invention.

Figure 1 is a broken perspective view of the invention shown in solid lines with a pressing iron in position with the iron not

in use. Dot and dash lines indicate a position of parts when the pressing iron is in use and elevated to press a sleeve on a sleeve board. Portions are broken away to contract the view.

Fig. 2 is an enlarged fragmental longitudinal sectional detail of the standard.

The hollow standard 1 may be of any suitable character and is preferably made of a section of pipe threaded at its lower end and screwed into the base 2 which may be attached to a table *a* by screws *b*. The upper end supports a sleeve 3 which is provided with anti-friction ball bearings 4, 5 at its upper and lower ends respectively and carried by the vertical stem 6. A main bracket 7 connected to said stem 6 by a union 8 is adapted to swivel in the sleeve 3 and is supported by the bearing 4 which contacts with the union 8. Nuts 9, 10 are screwed onto the lower end of the stem 6 to contact with the bearing 5 to secure the stem 6 in the sleeve.

The free end of the bracket 7 is provided with an elbow 11 and an upright 12, which is connected to a spindle 13 to which a second bracket arm 14 is journaled by a ball bearing hub 15, such for instance as that used for bicycles. Said bracket arm may be constructed in any suitable manner and is here shown as consisting of upper and lower limbs 16, 17, supporting spacer 18, with bolt 19, inserted therethrough; said spacer extending between arms 20, 21 projecting from the hub 15 and secured by the bolt 19 and nut 22.

The spindle 13 is secured in the hub 15 by a nut 23 screwed onto the end of the spindle. The second bracket arm 14 is provided at its outer free end with an elongate spring 24, the lower end of which spring is adjustably connected to the pressing iron 25 by a rod 26 that slides through a bearing secured to the lower end of said spring. A set screw 27 in the bearing secures the rod 26 in adjusted position in said bearing. The rod 26 is linked at its lower end to a connection 28 to which is attached at 29, the iron 25; said connection 28 being bent arc wise to escape the ordinary handle 30 of the pressing iron.

The spring 24 is of sufficient length to sustain the pressing iron 25 within an inch or two of the board when the rod 26 is in its extended position; and said spring is

likewise of such strength as to sustain the iron 25 out of contact with the board until downward pressure is applied.

When, as in using a sleeve board it is 5 desired to bring the iron to a higher level, the rod 26 is slid up and telescoped with the spring 24 and is secured by set screw 27 so as to normally sustain the iron 25 at any desired level as shown in dot and 10 dash lines in Fig. 1.

When not in use, the bracket arms 7 and 14 with their depending iron 25 automatically swing out of the way of the presser by means of the elongate spring 31 which 15 is attached at one end to an arm 32 of the spacer 28, and at the other end to an upright 33 clamped to the further side of the standard 1; said spring 31 thus tending to bring the free end of arm 14 and the 20 pressing iron 25 into close proximity to the standard 1. A stop 34 clamped to the arm 7 serves to prevent too great a movement of the arm 14 by action of the spring 31.

In practical operation the iron 25 may be 25 used within a large radius by means of the spring 24 and the movement of bracket arms 7 and 14, as indicated in dot and dash lines in Fig. 1; and when released will normally assume the position shown in solid lines in 30 said Fig. 1.

The iron may be adjusted to level position by horizontal movement of the limb 28' in the eye 29.

I claim.

- 35 1. In combination with a pressing iron and a pressing board, a standard secured to said board, a bracket swivelled in said standard, a bracket arm swivelled on said bracket, an elongate spring connected at one end to 40 said bracket arm, and at its other end to a bearing; a rod connected to said iron and extending through said bearing; and a set screw in said bearing for securing said rod in adjusted position therein.
- 45 2. In combination with a pressing iron and a pressing board, a standard secured

to said board, a bracket swivelled in said standard, a bracket arm swivelled on said bracket, resilient means for attaching the pressing iron to said bracket arm, means for 50 adjusting said iron to different heights above said pressing board, means to automatically swing the free end of said bracket arm into close proximity to said standard when the iron is not in use; and means 55 whereby said iron may be adjusted to a level horizontal position.

3. A support for a pressing iron comprising a standard; a sleeve within and supported by said standard; a horizontal 60 bracket having a vertical stem anti-frictionally swivelled in said sleeve; a bracket arm swivelled to the free end of said horizontal bracket; means for resiliently suspending a pressing iron from said bracket 65 arm and above a pressing board; and means for adjusting said pressing iron to different heights above said pressing board.

4. A support for a pressing iron comprising a standard; a bracket swivelled to said 70 standard; a bracket arm swivelled to the free end of said bracket; means adapted to resiliently support an iron from the free end of said bracket arm; and means to automatically swing the free end of said bracket 75 arm into close proximity to said standard when the iron is not in use.

5. A support for a pressing iron comprising a standard; a bracket swivelled to said standard; a bracket arm swivelled to the 80 free end of said bracket; means adapted to resiliently support an iron from the free end of said bracket arm; an upright clamped to said standard; and a spring attached at one end to said upright and at its 85 other end to said bracket arm.

In testimony whereof, I have hereunto set my hand at Los Angeles, California, this 17th day of November, 1922.

JOHN YOUNGBERG.

Witness:

JAMES R. TOWNSEND.
